UNITED STATES PATENT OFFICE.

EDMUND C. TOOKER, OF LARCHMONT, NEW YORK.

DESIGN FOR A CLASP-LOOP.

SPECIFICATION forming part of Design No. 22,677, dated August 8, 1893.

Application filed June 27, 1893. Serial No. 478,987. Term of patent 14 years.

To all whom it may concern:

Be it known that I, EDMUND C. TOOKER, a citizen of the United States, residing at Larchmont, in the county of Westchester and State 5 of New York, have invented and produced a new and original Design for the Loops of Garment-Clasps, of which the following is a specification, reference being had to the accompanying drawings, forming a part thereof.

- 10 My design relates to the loops of that form of garment clasps in which a loop engages with a hook or button; and my design is fully illustrated in the accompanying drawings, in which—
15 Figure 1 is a plan view of the loop, and Fig. 2 an end view of the same.
As shown in the figures, one end of the loop is expanded, being of a size such as to permit the head of the button or hook to pass through
20 it. The other end of the loop is contracted and is of a size such that it will closely embrace the shank of the button or hook.

The novel feature of my design consists in the form of the edges thereof. The inner edges of the loop are plain or smooth, while 25 the outer edges of the sides of the loop are indented, serrated, or of wavy outline, as shown. The contrast between the plain inner edges of the loops and the wavy outer edges causes the loop to present a graceful and pleasing effect to the eye, and relieves it of the severe plainness of loops formed with both edges 30 plain or smooth.

What I claim is—

The design for the loop of a garment clasp 35 herein shown and described one end of which is expanded and the other end contracted, the inner edges of the loop being plain or smooth, and the outer edges at the sides thereof having a wavy or serrated outline.

EDMUND C. TOOKER.
